(57) CLAIM

The ornamental design for a toothbrush holder, as shown and described.

DESCRIPTION

FIG. 1 is a perspective view of a toothbrush holder, showing our new design.

FIG. 2 is a top view thereof;

FIG. 3 is a front view thereof;

FIG. 4 is a bottom perspective view thereof;

FIG. 5 is a bottom view thereof; and,

FIG. 6 is another perspective view thereof.

The broken lines in FIGS. 2-3 depict portions of the toothbrush holder that form no part of the claim.
